UNITED STATES PATENT OFFICE

153,504

DESIGN FOR A CYCLE FENDER GUARD

Charles A. Comiskey, Chicago, Ill.

Application December 2, 1946, Serial No. 135,203

Term of patent 14 years

(Cl. D90—5)

To all whom it may concern:

Be it known that I, Charles A. Comiskey, a citizen of the United States, residing in Chicago, in the county of Cook and State of Illinois, have invented a new, original, and ornamental Design for a Cycle Fender Guard, of which the following is a specification, reference being had to the accompanying drawings, forming part thereof.

Fig. 1 is a perspective view of a cycle fender guard, showing my new design;

Fig. 2 is an end elevation of the guard;

Fig. 3 is a top view, and

Fig. 4 is a section on the line 4—4 on Fig. 3.

I claim:

The ornamental design for a cycle fender guard, substantially as shown.

CHARLES A. COMISKEY.
